His Attorney.

UNITED STATES PATENT OFFICE

ERNEST H. CHARLTON, OF SCHENECTADY, NEW YORK, ASSIGNOR TO GENERAL ELECTRIC COMPANY, A CORPORATION OF NEW YORK

ELECTRIC TIMING DEVICE

Application filed August 10, 1925, Serial No. 49,360. Renewed January 8, 1930.

My invention relates to apparatus for producing a desired time delay in the operation of electrical apparatus such as relays, intermittent signals and the like. The object of 5 the invention is to provide reliable, inexpensive, readily adjustable and accurate apparatus of this class.

In copending application Serial No. 49,359 filed concurrently herewith, I have described 10 electrical measuring apparatus which employs the use of a glow tube preferably associated with a condenser for storing energy in such a manner that when a predetermined amount of energy has been accumulated it is 15 discharged through the glow tube to produce a measuring indication. I have discovered that the same principle may be employed to produce intermittent signals and time delay relay operations having a wide variety of 20 applications.

The features of my invention which are believed to be novel and patentable will be pointed out in the claims appended hereto. Several modifications of the apparatus will 25 be described in connection with the accompanying drawing, which illustrates the use of the invention for operating flashing lamps, or the same scheme may be used as a relay which operates after being energized for a 30 predetermined time.

Referring to the drawing, 10 represents a glow tube. It is shunted by a variable condenser 11. The glow tube and condenser are connected in the plate circuit of an electron 35 discharge device 12 and the apparatus is supplied from a source 17 which may be an ordinary direct or alternating current circuit of 110 volts. This source may be of sufficient voltage to cause the glow tube 10 to flash. 13, 40 14 and 15 represent the filament, grid and plate of the device 12, and the filament is heated by the usual battery 16.

When the switch at 18 is closed, the device 12 will, when properly adjusted, produce a 45 constant current discharge from the plate 15. This will first charge the condenser 11 up to a potential corresponding to the flashing voltage of glow tube 10. The tube will flash and discharge the condenser. The rate of 50 flashing can be timed by adjusting the varia-

ble condenser 11. Thus if the capacity is increased, it will take that much longer for it to build up to the sparking voltage of the glow tube. The glow tube 10 may constitute a signal or lamp flashing device in itself or 55 the discharge current from the condenser may operate a relay 19 to close the circuit of lamps 20, or both the device 10 and lamp shown at 20 may constitute light signals.

It will be understood that the relatively 60 small charging current of the condenser will be insufficient to operate the relay 19, but the sudden discharge current will be ample for this purpose.

The same arrangement may be used as a 65 time delay for relay 19, since it is evident that the relay 19 will operate a predetermined adjustable time after switch 18 is closed. The switch 18 may be closed manually or by any other agency.

In accordance with the provisions of the 70 patent statutes, I have described the principle of operation of my invention, together with the apparatus which I now consider to represent the best embodiment thereof; but I desire to have it understood that the apparatus 75 shown is only illustrative and that the invention may be carried out by other means.

What I claim as new and desire to secure by Letters Patent of the United States, is:

1. An electric timing device comprising a 80 glow tube and a condenser connected in parallel, a source of supply having a voltage in excess of the sparking voltage of said glow tube, and means for charging said condenser 85 from said source at a substantially constant rate.

2. An electric timing device comprising a 90 glow tube and a variable condenser connected in parallel, a source of supply having a potential in excess of the sparking potential of said glow tube, and means for charging said condenser from said source at a substantially constant rate.

3. An electric timing device for a relay 95 comprising a glow tube and a condenser connected in parallel, a source of supply having a potential in excess of the sparking voltage of said glow tube, a relay included in the circuit of said condenser, and means for 100

charging said condenser from said source at a substantially constant rate below that necessary to operate the relay up to the sparking potential of said glow tube, said relay being 5 operable by the discharge current of said condenser.

4. An electric timing device for relays comprising a glow tube and a condenser connected in parallel, a source of supply having 10 a potential in excess of the sparking voltage of said glow tube, a relay included in the circuit of said condenser, means for charging said condenser at a substantially constant rate below that necessary to operate the relay, 15 said relay being operable by the discharge current of said condenser, and means for varying the time required for said condenser to become charged to the sparking potential of said glow tube.
- 20 5. An electric timing device comprising a glow tube and a condenser connected in parallel, a source of supply having a potential in excess of the sparking potential of said glow tube, an electron discharge device for 25 continuously charging said condenser from said source, and means for varying the time required for said condenser to become charged to the sparking potential of said glow tube.
- 30 6. An electric timing device for relays comprising a glow tube and a condenser connected in parallel, an electron discharge device for charging said condenser, said electron discharge device and glow tube being 35 connected across a source of supply having a voltage in excess of the sparking voltage of said glow tube, a relay connected in the circuit of said condenser, said relay being operable by the discharge current of said condenser but not by the charging current.
- 40

In witness whereof I have hereunto set my hand this eighth day of August, 1925.

ERNEST E. CHARLTON.
